CLAIM

The ornamental design for a bottle holder for belts, as shown and described.

DESCRIPTION

FIG. 1 is a right side elevational view of a bottle holder for belts showing my new design, the opposite side being a mirror image.

FIG. 2 is a top plan view thereof.

FIG. 3 is a bottom plan view thereof.

FIG. 4 is a front elevational view thereof.

FIG. 5 is a perspective view thereof.

FIG. 6 is a right side elevational view of a second embodiment of my bottle holder for belts, the opposite side being a mirror image.

FIG. 7 is a top plan view thereof.

FIG. 8 is a bottom plan view thereof.

FIG. 9 is a front elevational view thereof; and,

FIG. 10 is a perspective view thereof.
